UNITED STATES PATENT OFFICE.

FRANK S. WESTBROOK, OF GREENSBORO, NORTH CAROLINA.

CANOPY.

1,007,829.

Specification of Letters Patent.

Patented Nov. 7, 1911.

Application filed April 11, 1911. Serial No. 620,400.

To all whom it may concern:

Be it known that I, FRANK S. WESTBROOK, a citizen of the United States, residing at Greensboro, in the county of Guilford and State of North Carolina, have invented certain new and useful Improvements in Canopies; and I do hereby declare the following to be a full, clear, and exact description of the same, reference being had 10 to the accompanying drawings, forming a part of this specification, and to the figures and letters of reference marked thereon.

This invention relates to improvements in canopies adapted to be placed on a bed, 15 crib or other support as a protection against flies, mosquitos, etc. and it has for its object to provide such a device that may be readily opened out for use or collapsed for transportation or storage.

20 To these ends the invention consists in certain novel details of construction and combination of parts, all as will be now described and the particular features of novelty pointed out in the appended claims.

25 In the accompanying drawings wherein is illustrated the preferred embodiment of the present invention,—Figure 1 is a perspective of the canopy in open position; Fig. 2 is a detail view of one of the hinged 30 side supports for the frames, the frames being partly broken away and shown in open position with one form of lock; Fig. 3 is a detail view of the support, with the frames in open position, showing a modified form 35 of lock; Fig. 4 is a similar view showing the frames in closed position; and Fig. 5 is a detail section on line $x-x$ of Fig. 2.

Similar letters of reference in the several figures indicate the same parts.

40 Referring to the accompanying drawings, the side pieces or supports for the netting frames or bows, consist of two members A and B, pivoted or hinged together as at C. These hinged members are formed preferably of sheet metal bent to proper shape. 45 Bows or frames D, E formed of metal bars and bent to the desired shape, are fixedly secured at each end to the hinged members A and B, preferably by soldering. These 50 frames when the canopy is opened out, as in Fig. 1, form a base or support for the canopy, as will be readily understood. Intermediate frames F, G, H and I, also formed of metal bars and bent to proper shape, are 55 pivotally mounted on the hinged side pieces,

the pivotal connection being secured by forming eyes f, g, h and i, at the ends of the frames, which take over rivets J and K. Preferably the eyes are flattened so that the ends of two frames may be secured to one 60 rivet, as shown in Fig. 5. The frames are covered with netting L or other fabric which is secured to the frames in any suitable way. Preferably the netting extends below the bottom frames D, E, in the form of a flounce 65 or valance N, so that it will effectually close any space between the bottom of the canopy and the bed or other support upon which the canopy may be placed.

In order to hold the hinged side supports 70 open or closed a lock is provided which in one embodiment consists of a spring O formed of a piece of wire of suitable size and weight, bent to form a coil o, the ends of the wire being crossed and secured about 75 the rivets J K beneath the heads o' thereof.

In Fig. 4 there is shown a modified form of lock, consisting of a hooked latch P pivotally mounted on one hinge member as at p and coöperating with a headed stud p' on 80 the other hinge member.

From the above description it will be seen that when the frames are opened out the frames C and D, fixedly secured to the side pieces, form a fixed base or support, the intermediate pivoted frames assuming the proper position to hold the netting under tension. The device consists of few parts, can be readily folded into small compass and packed in a trunk or carried from place to 90 place.

Having thus described the invention, what I claim and desire to secure by Letters Patent, is:

1. In a device such as described, the combination with the hinged side pieces or supports, of frames fixedly secured to said hinged pieces, and intermediate frames pivotally mounted on said hinged pieces. 95

2. In a device such as described, the combination with the hinged side pieces or frame supports, of frames fixedly secured to said hinged side pieces, whereby when in open position said frames will constitute a base for the canopy, intermediate frames pivotally mounted on said side pieces, and a lock for holding said side pieces in either open or closed position. 100

3. In a device such as described, the combination with the hinged side pieces or 110

frame supports, of frames secured fixedly to said hinged side pieces, whereby when in open position said frames will constitute a base for the canopy, intermediate frames 5 pivotally mounted on said side pieces, and a coil spring having its ends crossed and secured one to each member of the side pieces

for holding said side pieces in either open or closed position.

FRANK S. WESTBROOK.
